UNITED STATES PATENT OFFICE.

ABRAM C. MOTT, OF PHILADELPHIA, PENNSYLVANIA.

DESIGN FOR A BOILER-SECTION FOR FURNACES.

SPECIFICATION forming part of Design No. 26,997, dated April 27, 1897.

Application filed March 20, 1897. Serial No. 628,542. Term of patent 14 years.

To all whom it may concern:

Be it known that I, ABRAM C. MOTT, a citizen of the United States, residing in Philadelphia, Pennsylvania, have invented a certain 5 new and useful Design for a Boiler-Section, of which the following is a specification.

My design for a boiler-section of a steam or hot-water furnace is fully illustrated in the accompanying drawings, in which—

10 Figure 1 is a perspective view showing the outside of the boiler-section. Fig. 2 is a perspective view showing the inside of the boiler-section. Fig. 3 is an end view, and Fig. 4 is an end view of a modified form.

15 This boiler-section forms one of the side plates of the boiler, inclosing the fire-pot and combustion-chamber.

The essential feature of the design is the wide upper section having longitudinal ribs

20 and the flat lower section.

A is the upper portion of the boiler-section, being flat on one side and recessed at a on the opposite side, and within this recess is a lon-

gitudinal rib a' . The upper corners of this section are rounded, and the top is slightly 25 curved.

The inner face b of the lower portion B of the section is arranged at a slight incline. The lower portion has a vertical rib b' at one end and is notched at the opposite end. The 30 face b^2 of the lower section may be inclined, as in Fig. 3, or vertical, as in Fig. 4.

The entire structure is hollow, and in the rear of the lower portion are circular enlargements c .

35 I claim—

The design for a boiler-section as herein described and as shown in the accompanying drawings.

In testimony whereof I have signed my 40 name to this specification in the presence of two subscribing witnesses.

ABRAM C. MOTT.
